UNITED STATES PATENT OFFICE.

JOHN J. KOONS, OF SARATOGA SPRINGS, NEW YORK.

CASE FOR STORING BOTTLES.

SPECIFICATION forming part of Letters Patent No. 787,300, dated April 11, 1905.

Application filed April 20, 1904. Serial No. 204,105.

To all whom it may concern:

Be it known that I, JOHN J. KOONS, a citizen of the United States, residing at Saratoga Springs, in the county of Saratoga and State 5 of New York, have invented new and useful Improvements in Cases for Storing Bottles, of which the following is a specification.

My invention relates to shipping-cases; and its primary object is to provide a new and useful device of this character in which bottles 10 may be transported without liability of becoming broken, which will be cheap to manufacture, durable, and efficient, and in which bottles may be packed in such a manner that 15 waste of space is reduced to a minimum.

A further object of the invention is to provide a case of the above-stated character with a movable head so constructed and arranged that it may be easily and quickly moved to 20 clamp the bottles in their applied position.

The invention consists in the construction, combination, and arrangement of parts hereinafter fully described, claimed, and illustrated in the accompanying drawings, which 25 disclose the preferred form of my invention, and in which—

Figure 1 is a top plan view of a case constructed in accordance with my invention, the cover thereof being removed. Fig. 2 is a 30 transverse sectional view thereof, the cover being in closed position. Fig. 3 is a section on line 3-3 of Fig. 2. Fig. 4 is a similar view on line 4-4 of Fig. 2. Fig. 5 is a central longitudinal sectional view of a modified form of 35 the invention wherein the movable head is shown in position to permit the application and removal of the bottles. Fig. 6 is a view similar to Fig. 5, the head in this view being shown in position to clamp the bottles in applied position. Fig. 7 is a detail perspective 40 view of the head.

Referring to the drawings by reference-numerals, 1 designates the bottom, 2^a and 2^b the ends, 3-3 the sides, and 4 the cover, of a 45 case constructed in accordance with my invention.

For the purpose of convenience in illustrating and describing the invention I have shown the same in the drawings as adapted 50 to receive six bottles for transportation; but

I wish it to be understood that it may be constructed to receive any number of bottles. The bottles are adapted to be packed in horizontal rows one above the other, the bottles in each row being arranged in reverse direction to the row beneath them and each bottle being arranged in reverse direction to the adjacent bottle, as fully disclosed in Figs. 1 and 2 of the drawings. This arrangement of the bottles reduces the waste of space to a minimum, as is apparent from the disclosure in the drawings.

To permit of the above arrangement of the bottom or lower row of bottles and to secure them in position against accidental breakage, 65 I provide the inner face of the end 2^a of the case with circular grooves 5, which are adapted to receive the bottom of two bottles, and the inner face of the end 2^b with elongated grooves 6, which are arranged diametrically 70 opposite the grooves 5, to receive the upper ends of said bottles. Situated between the grooves 6 in the inner face of the end 2^b is a circular groove 7, adapted to receive the bottom of the third or center bottle of the row, 75 and situated between the grooves 5 in the inner face of the end 2^a is an elongated groove 8, adapted to receive the upper end of the said bottle.

It is apparent from the above description, 80 taken in connection with the accompanying drawings, that the arrangement of the grooves permits of the lower row of bottles being packed in the case in a horizontal position and each bottle being arranged in reverse direction to the adjacent one.

To permit of the upper row of bottles being arranged in the manner hereinbefore pointed out and to secure them in applied position, I provide the inner face of the end 2^b 90 above the grooves 6 with circular grooves 9, adapted to receive the bottoms of the two end bottles of the upper row, said grooves communicating with the grooves 6 to permit of the end bottles of the lower row being inserted 95 in the grooves 5 and 6. To receive the opposite or upper ends of the bottles, elongated grooves 10 are situated in the inner face of the end 2^a diametrically opposite the grooves 9 and above the grooves 5. These grooves 100

have their upper ends open along the upper edge of the end 2^b to permit the bottles to be readily inserted in the grooves 9 and 10. In the inner face of the end 2^a, between the 5 grooves 10 and communicating with the groove 8, is a circular groove 11, adapted to receive the bottom of the center bottle of the upper row, and to receive the opposite or upper end thereof I locate an elongated groove 12 in the 10 inner face of the end 2^b and between the grooves 9 and above the grooves 7. As the groove 11 communicates with the groove 8 the center bottle of the lower row may be readily inserted in applied position.

15 The ends of the bottles are adapted to be inserted in the grooves by first placing the bottoms of the bottles in the circular grooves and then placing the upper ends of the bottles in elongated grooves in a manner that is 20 apparent.

The cover 4 of the case is adapted to be hingedly secured to one of the ends thereof, and it is adapted to be secured in closed position by any improved fastening means.

25 In the modified form of my invention I disclose the case provided with a movable head or follower 13, which is adapted to be moved to clamp the bottles between itself and the end 2^a. This head or follower is provided 30 with grooves similar to those in the end 2^b in the preferred form of the invention, and it is provided with a centrally-located screw-threaded opening 14, which is adapted to receive the threaded end of a bolt 15, journaled 35 in the end 2^b. The bolt 15 is provided with an enlarged annular portion 16, journaled in an opening in the end 2^b and held therein by means of plates 17 and 18. The outer end of 40 the bolt 15 is provided with a groove (not shown) which extends transversely there-across in order that the bolt may be rotated, by means of a screw-driver, to either move the head or follower toward the end 2^a to clamp the bottles in applied position or away 45 from said end to permit the bottles to be either placed within or moved from the case.

It is apparent that the bolt 15 not only adjusts the follower to clamp the bottles against movement between the end 2^a and the inner 50 face of the follower, but it also retains the follower in its adjusted position.

From the foregoing description, taken in connection with the accompanying drawings, the construction and advantage of my improved shipping-case will be readily apparent without requiring any further extended explanation. It will be seen that the device is simple of construction, that said construction permits of its manufacture at small cost, and 60 that it is exceedingly well adapted for the purpose for which it is designed.

Having thus described the invention, what I claim as new is—

1. A case of the class set forth having the 65 inner face of one of its ends provided near its

lower edge with circular grooves and an elongated groove and near its upper edge with elongated grooves and a circular groove; and having the inner face of its other end provided near its lower edge with elongated grooves 70 opposite the lower circular grooves of the first-mentioned end and a circular groove opposite the lower elongated groove of the first-mentioned end and provided near its upper edge with circular grooves opposite the upper 75 elongated grooves of the first-mentioned end and an elongated groove opposite the upper circular groove of the first-mentioned end, substantially as shown and described.

2. A case of the class set forth having the 80 inner face of one of its ends provided near its lower edge with circular grooves and an elongated groove located between the circular grooves and near its upper edge with elongated grooves and a circular groove located 85 between the elongated grooves and communicating with the lower elongated groove; and having the inner face of its other end provided near its lower edge with elongated grooves opposite the lower circular grooves of the first- 90 mentioned end and a circular groove between the elongated grooves and opposite the lower elongated groove of the first-mentioned end and near its upper edge with circular grooves opposite the upper elongated grooves of the 95 first-mentioned end and communicating with the lower elongated grooves of the last-mentioned end and an elongated groove opposite the upper circular groove of the first-mentioned end. 100

3. A case of the class set forth, having the inner face of one of its ends provided near its lower edge with circular grooves and an elongated groove and near its upper edge with elongated grooves and a circular groove, a 105 follower arranged in the case and provided near its lower edge with elongated grooves opposite the lower circular grooves of said end and a circular groove opposite the lower elongated groove of said end and provided 110 near its upper end with circular grooves opposite the upper elongated grooves of said end and an elongated groove opposite the upper circular groove of said end, and means for moving said follower. 115

4. A case of the class set forth, having the inner face of one of its ends provided with grooves, a follower arranged in the case and provided with grooves, and a bolt journaled in the other end of the case and having threaded connection with the follower, whereby the follower may be moved toward and away from the first-mentioned end. 120

5. A case of the class set forth having the inner face of one of its ends provided with 125 grooves, a follower arranged in the case and provided with grooves, the other end of said case being provided with an opening, a bolt having an enlarged portion journaled in said opening and having threaded connection with 130

the follower, whereby said follower may be moved toward and away from the first-named end, and means for retaining the bolt in applied position.

5 6. A case of the class set forth having the inner face of one of its ends provided with grooves, a follower arranged in the case and provided with grooves, the other end of said case being provided with an opening, a bolt 10 having an enlarged portion journaled in said opening and having threaded connection with the follower, whereby said follower may be moved toward and away from said first-mentioned end, the outer end of said bolt being 15 provided with a groove, and plates secured to the last-mentioned end to retain the bolt in applied position.

7. A case of the class set forth having the inner face of one of its ends provided with a 20 circular groove, and the inner face of its other end provided with an elongated groove and a circular groove having communication with each other, said last-named elongated groove arranged in alinement with the first-named 25 circular groove.

8. A case of the class set forth having the inner face of one of its ends provided with a circular groove, and an elongated groove, and the inner face of its other end provided with

an elongated groove opposite said circular 30 groove and a circular groove opposite the first-named elongated groove, said last-named circular and elongated grooves communicating with each other.

9. A case of the class set forth having the 35 inner face of one of its ends provided with a circular groove, a follower provided with a circular groove and an elongated groove communicating with each other, said elongated groove being arranged opposite said first- 40 named circular groove, and means for adjusting the follower.

10. A case of the class set forth having the inner face of one of its ends provided with an elongated groove, and a circular groove, a follower arranged in the casing and having a circular groove opposite the elongated groove and an elongated groove opposite the first-named circular groove, said last-named circular and elongated grooves communicating with 50 each other, and means for adjusting the follower.

In testimony whereof I affix my signature in presence of two witnesses.
